3,044,211 TOY OBJECTS

Felix Palm, 2241 W. Greenleaf Ave., Chicago 45, Ill.
Filed July 17, 1959, Ser. No. 827,878
4 Claims. (Cl. 46—11)

My invention relates to cardboard box conversions, and more specifically a method of converting cardboard boxes such as cereal boxes and the like into toys or novelty objects, and to boxes of this character, appropriately marked and bearing instructions for making such objects.

It is well known that the sales of breakfast cereals and other household materials packaged in comparable boxes enjoy substantially greater sales when more than just the packaged commodity is provided. These extra sales inducements may take the form of enclosures, box-top premium offers, games or novelties printed on the cardboard of the carton, etc. My invention is directed to the fabrication of toy objects from cereal boxes and the like by a simple cutting, folding, removal of certain areas, etc., according to appropriate instructions on the box after the contents of the box have been exhausted, to provide such additional sales value.

In the following description, I have described my invention as particularly applied to the construction of a toy barn or comparable toy building and an Easter box from representative cereal boxes or similar containers.

One object of my invention, therefore, may be regarded as a method for converting cardboard containers such as cereal boxes and the like into models, toys and novelties. More specifically, this object may be regarded as a method for making such objects as model buildings or baskets from such boxes.

Another object of my invention is the provision of a model building or basket made from a package of this character. Still another object resides in the design and marking of a container of this type, whereby such models, toys or novelties may be easily constructed from them in simple fashion, while at the same time ample exterior box surface is left for labels, advertising matter, instructions, etc.

A still further object of my invention resides in the marking of a cereal box for the construction of model buildings, baskets, etc. therefrom, so that such toys may be easily constructed from the box by a very young child.

Other objects and advantages of my invention will be apparent from the following directions and drawings, of which:

FIG. 1 is a perspective of a cereal box shown front face up, marked and cut away in part in accordance with one application of my invention as a step in the construction of a toy barn therefrom;

FIG. 2 is a perspective view of the box of FIG. 1 shown back face up;

FIG. 3 is a longitudinal section through the box of FIG. 1 showing the barn in a further stage of construction;

FIG. 4 is a perspective of a completed barn made from the box of FIG. 1;

FIG. 5 is a transverse section through the barn of FIG. 4;

FIG. 6 is a perspective view of a cereal box, front face up, marked and partially cut away as a stage in the construction of a portable basket therefrom;

FIG. 7 is a perspective view of the box of FIG. 6 shown back face up;

FIG. 8 is a view similar to FIG. 7, showing, however, the box in a further stage of construction;

FIG. 9 is a view similar to FIG. 8, showing the completed box; and

FIG. 10 is a vertical transverse section through the

2

box of FIG. 9 taken on the line 10—10 of FIG. 9, looking in the direction of the arrows.

In FIG. 1 is shown a cereal box 10 which is representative of the type of package to which my invention is directed. It will be appreciated, of course, that my invention may be applied to any rectangular cardboard box or container, but a cereal box is a package to which my invention is particularly likely to be applied.

FIG. 1 shows the box with the front face or side 12 up, that being the side intended to carry the trademark, advertising, etc. In the practice of my invention, that side will have indicated a central transverse line 14 along which that side is to be cut, and score lines 16, parallel to and spaced somewhat from line 14, along which that side of the box is to be folded. It will be appreciated that these lines may be indicated by marks at the side of the face of the cereal box rather than by lines extending across the face of the box if such lines should be found to impair or detract from the advertising value of the front face of the box.

The back 18 of the box as seen in FIG. 2 is printed with the representation of a barn side 20 at the ends thereof, and the central portion 22 may be printed with the representation of a roof. The back 18 is marked with a central transverse score line 24 and two score lines 26 at the meeting edges of the central roof area 22 and the end, barn-side areas 20. The roof, in this embodiment, is a simple gable roof, but other roof forms are well within the capability of my invention.

The ends 28 of the box are unmarked for purposes of the practice of my invention and are available for display space.

The sides 30 of the box are employed to represent the ends of the barn. Each end 32 of the sides of the box is imprinted with a representation of a vertical half barn end. The barn end halves are oriented with their bottom edges at the side ends 34, the outer end of the roof line 35 meeting the back sides 18 of the box at the end of line 26 and the roof peak meeting the ends of the score lines 16 on the front face 12 of the box at points 38. It will be appreciated that a central trapezoidal area 40 is defined in the center of the cereal box sides between the barn end halves which requires no marking and is thus available for display space.

In the course of marking the container for conversion to the illustrated barn, the siding and roofing, together with windows 42, doors 44 and hay doors 46, may be printed on the back 18 and sides 30 of the box to make the completed barn more realistic in detail and thus more attractive to children.

It will be understood from the foregoing description that certain of the lines provided on the cereal box in the pursuance of my invention are to indicate folds and other lines to indicate lines of cutting. Either type of line may be simply printed on the box or some, particularly those indicating the lines of cut, may be perforated so that the toy may be made without the use of scissors.

It is believed that the construction of the toy barn from the cereal box as described above will be evident from the drawings. The trapezoidal areas 40 are cut away from the sides of the box. The front face of the box is cut transversely across on line 14. The areas on either side of line 14 between the cut edge and the parallel lines 16 are creased inwardly along lines 16 to provide strengthening tabs 48.

Glue or paste may be applied to the outside surface of the tabs 48 (the exposed surface of FIG. 1) and the tabs bent to conform to the angle the barn roof makes with the vertical.

The back of the box is folded along line 24 and again along lines 26 to define the ridge and the outer edges of the roof. The barn halves on the end portions of the box

are then rolled toward each other as illustrated successively in FIG. 3 and FIG. 5, so as first to bring the tabs 48 against the underside of the roof surface on either side of the ridge line 24, as particularly seen in FIG. 3, and then further rolled to form the angularity of the roof and bring the two portions of the front face of the box together, as illustrated in FIG. 5. Paste or glue may be applied to the outside surfaces of the front face portions to secure them together against one another. Alternatively, the two halves of the barn may be secured together in the relation of FIG. 5, by pressure-sensitive adhesive tape extending across the bottom of the barn.

It will be appreciated that the tabs 48 will inevitably exist in that, no matter what the pitch of the roof, the roof peak points of each barn half must be somewhat separated from each other. The distance from the eaves line 26 to the center line 24 of the roof is necessarily shorter than a line extending from the eaves line 26 angularly across the sides of the box to the line of cutting 14.

FIGS. 6 through 10, showing an Easter basket, are illustrative of another way in which a breakfast food box or comparable container may be used for toy construction. In FIG. 6, the cereal box is shown front side 52 up. This side again is entirely available for brand name, advertising, instructions, etc. The box ends 54 constitute the bottom of the basket and therefore they likewise are freely available for display. The box sides 56 have a large central portion cut away as will be later described and this center portion is therefore also available for display.

In this application of my invention, the box is so marked as to define two end receptacle portions 58. These portions together constitute the body or base 60 of the basket, the ends 54 of the box together comprising the bottom of the basket. The receptacle portions are defined generally by areas to be cut out of the central portion of the box, all of these areas being based generally on lines 62 which define the top edge of the basket or receptacle portions 58.

The sides 56 of the box are cut away nearly entirely between lines 62 so as to leave only two small tabs 64, connected on each side to the back side of the box. The tabs are separated by a central notch 66 extending to the back face of the box. The front face of the box is cut away at its sides between lines 62 to lines 68 inwardly of the side edges of the front face 52. The removal of these portions of the front face results in a broad strap interconnecting the end receptacle portions 58. Rectangular areas defined by lines 72 and extending to lines 62 are removed from the strap so as to convert the strap into an H-shaped link 70 having a cross-piece 74 of substantial width in the center of the front face of the box. A score or crease line 76 is marked on the precise transverse center line of the box face extending longitudinally of the crosspiece 74.

The back 78 of the box is particularly illustrated in FIG. 7. The back of the box is marked for the removal of a central transverse strip to define a slot 80. The slot 80 is wide enough to receive comfortably, but snugly, a doubled thickness of the cardboard of which the box is made and is slightly longer than the width of the H-shaped link.

Fold lines 82 are indicated on the back of the box, close and parallel to slot 80. Lines 84 are indicated which extend from the ends of lines 82 to the base line 62. Lines 84 and the portion of lines 62 between lines 84 are to be cut. To make the basket from the box, the indicated cutting operations are performed to remove the indicated box portions or partially detach them as the case may be. FIGS. 6 and 7 are illustrative of a box so prepared. Thereafter, the ends of the box are rolled toward each other in a direction to fold or collapse the H-shaped link 70. The link 70 is creased along score line 76 so that the link collapses inwardly. Upon further rolling, the

two edges of the link come together and the fold 76 is guided through slot 80. The rolling is further continued until the front face portions 52 of the box ends come together as best illustrated in FIG. 9. In the course of the final rolling of the box ends or receptacle portions, the tabs 64 are guided to lodge inside the box ends as best seen in FIG. 8. The notches 66 are provided to permit edges 62 of the front face to lie flat against the back side of the box. The front face portions 52 of the receptacle may be glued or pasted together so as to hold the basket in its finished form illustrated in FIG. 9 or, again, pressure-sensitive tape may be used across the two parts of the bottom of the basket.

It will be appreciated that the folded H-shaped link 70 constitutes a handle of double thickness and strength in the completed basket and semi-detached flaps 86 defined by crease lines 82 and lines of cut 62 and 84 constitute covers for the basket halves.

It will be appreciated from the foregoing description that I have devised an entirely new and novel use for cardboard containers such as cereal boxes and the like, whereby such containers, after their contents are exhausted, can be used to make various objects of a novel nature which should substantially enhance the sales value of the packaged products. The principle of conversion implicit in my invention is one which will provide entertainment and result in as substantial and sturdy devices as the nature of the material permits. My invention further permits the making of a pre-decorated object without visible manufacturers' markings or labels thereon, from a container which possesses ample room for trade names and advertising, including one entire face of the carton.

The generic feature underlying the above-described embodiments of my invention is, of course, dividing the object to be formed into two halves and so designing the object that it may be constructed by cutting away or providing for a collapse of a central portion of the container and thereafter folding the container so that each part thereof on either side of the fold may constitute one of the halves of the object. It is this folding which makes possible the unmarked, one face of the container for advertising or display space (that being the surface of inward folding) while at the same time permitting a printing of the container appropriate to the object so that when the object is completely constructed all exterior surfaces thereof are appropriately ornamented or colored.

It should, of course, be understood that while I have frequently referred herein to cereal boxes as being useful in carrying out my invention, boxes and containers of a wide variety of types and sizes may also be used for that purpose. Indeed, much larger paperboard or card board or similar material cartons may be used without departing from the teachings set forth herein and it should be understood that such container are also included when I have referred to cereal boxes.

It will be understood that I have described above embodiments only of my invention and that my invention should be regarded as being limited only as set forth in the following claims.

I claim:

1. A cardboard container comprising a front, wide rectangular face printed to identify the contents of said container, a rear, wide rectangular face the same size and shape as said front face printed on both sides of its transverse centerline with the printing on either side of the transverse centerline similarly directionally oriented with respect to said centerline, rectangular side panels connecting the corresponding long edges of said front and back panels, rectangular end panels connecting the corresponding short edges of said front and back faces, said end and said panels cooperatively positioned with said front and rear faces to form a closed container, lines indicating where to cut said front face and said side panels with said lines across said side panels non-divergent away

from said rear face, to produce an opening across said front face and across said side panels symmetrical about the centerline of said front face, a plurality of scored lines across said rear panel which are parallel to each other and to the transverse centerline across said rear panel with said scored lines positioned with respect to said cutting lines whereby when severance is effected along said cutting lines, the rear face is adapted to be folded along said scored lines to bring the uncut portions of said front face on opposite sides of said transverse centerline into contact with each other to form a toy with the front face hidden from view.

2. A cardboard container comprising a front wide rectangular face printed to identify the contents of said container, a rear wide rectangular face the same size and shape as the front face printed about its transverse centerline to define central roof sections and marginal wall sections with scored lines at the intersections of said roof sections and wall sections and along said transverse centerline, rectangular side panels connecting the corresponding long edges of said front and back faces, rectangular end panels connecting the corresponding short edges of said faces, said side panels and end panels cooperatively positioned with said front and rear faces to form a closed container, a transverse centerline on said front face indicating where said front face should be cut, scored transverse lines parallel to said last mentioned centerline and spaced symmetrically on either side of it, straight lines indicating where cutting should be effected connecting the points where said parallel scored transverse lines intersect the lines where said front face intersects said side panels, then connecting the ends of the parallel scored lines on said front face to the ends of the scored lines between the wall sections and roof section on said rear face and then between the ends of the last mentioned scored lines whereby diagonal lines that converge away from said roof section result across said side panels, the positions of said scored lines on said front panel and said rear panel being such that the resultant diagonal lines are one half the length of said roof section.

3. A cardboard container comprising a front wide rectangular face printed to identify the contents of said container, a rear wide rectangular face of the same size and shape as said front face printed on both sides of its transverse centerline similarly directionally oriented with respect to said centerline, rectangular side panels connecting the corresponding long edges of said front and back faces, rectangular end panels connecting the corresponding short edges of said front and back faces, said end and side panels cooperatively positioned with said front and rear faces to form a closed container, lines indicating where to cut the front face inwardly from the intersection of said front face with each side panel parallel to the transverse centerline and spaced therefrom a distance equal to the width of said side panel, said lines extending toward the longitudinal centerline of said front face to points from about 5" to about 8" from each other, said lines extending across said panels perpendicular to the longitudinal axis thereof to the intersection of said side panels with said rear face, said front face scored on its transverse centerline and slotted symmetrically about said transverse centerline and said longitudinal centerline with slots about 3" to about 5" in length and at least 2" in width spaced with their long axis parallel to the transverse centerline, spaced symmetrically on either side of said transverse centerline and intersecting the longitudinal centerline, lines indicating the position to cut said rear face in a slot symmetrical about and including the transverse centerline of said rear face, said slot being not in excess of 1" in width and being greater in length than the width of the remaining portion of said front face.

4. The container of claim 1 further characterized in that said lines indicating the position to cut are perforated lines which may be severed by punching-out.
